(57) **CLAIM**

The ornamental design for a portion of a vehicle interior, as shown and described.

DESCRIPTION

FIG. 1 is a front elevational view of a portion of a vehicle interior showing our new design;

FIG. 2 is a perspective view of one side thereof; and,
FIG. 3 is a perspective view of the opposite side thereof.
The even broken line showings of the front seats, dashboard,
doors, windshield, and front bulkhead in FIG. 1; the rect-
angular areas in FIGS. 2-3; the geometric elements on
the wheel wells in FIGS. 1-3; and the handle elements in
the floor in FIGS. 1-3 are for illustrative purposes only and form
no part of the claimed design. FIGS. 2-3 depict only a
portion of the floor area by necessity. The heavy, uneven
broken line in FIGS. 2-3 forms no part of the claimed
design, but rather is intended to illustrate that the claim
continues beyond that line as seen in FIG. 1. The heavy,
broken, jagged line in all of the figures is intended to denote
a boundary of the claimed design and forms no part of the
claimed design.
